(57) **CLAIM**

I claim the ornamental design for a shelving bracket, as shown and described.

DESCRIPTION

FIG. 1 is a perspective view of the shelving bracket.

FIG. 2 is a front elevation view of the shelving bracket.

FIG. 3 is a top plan view of the shelving bracket.

FIG. 4 is a side elevation view of the shelving bracket looking from the left side of FIG. 1.

FIG. 5 is a side elevation view of the shelving bracket looking from the right side of FIG. 1.

FIG. 6 is a rear elevation view of the shelving bracket; and, FIG. 7 is a bottom plan view of the shelving bracket.
